UNITED STATES PATENT OFFICE.

JOHN C. QUINN, OF NEW YORK, N. Y., ASSIGNOR TO THE ACME FURNACE EQUIPMENT COMPANY, OF NEW YORK, N. Y., A CORPORATION OF NEW YORK.

METHOD OF BURNING BRICKS.

1,102,546.

Specification of Letters Patent.

Patented July 7, 1914.

Application filed January 15, 1913. Serial No. 742,203.

To all whom it may concern:

Be it known that I, JOHN C. QUINN, a citizen of the United States, residing in the city, county, and State of New York, have invented the following described Improvements in Methods of Burning Bricks.

My invention is an improved method of manufacturing bricks, seeking to improve the efficiency of the firing process, and consists in the succession of steps hereinafter described in detail and more particularly defined in the appended claims.

In the accompanying drawings forming part of this application I have shown in diagram in Figure 1 a layout of an ordinary brick kiln, the figure representing a section of the kiln at the plane of the several grates thereof. Fig. 2 is a section view of such a kiln, and it may be here stated that the construction and arrangement is a commonplace one.

In the drawings the parts marked 1 represent the permanent walls of the kiln, and 2 represents the permanent floor thereof. The ash-pits 3 are formed in or slightly below the level of the floor 2, and are provided with the usual grates 4. It is customary to divide the grate surface of each of the fire-places into four sections, as shown, and I will describe my process with reference to such sections, although it will be understood by those skilled in this art that the entire grate area can be made of one section or of any number desired. Each ash-pit has a door 5 for the removal of ash, and a connection, preferably under ground, with a duct or flue 6 which leads from a fan blower 7, driven by a prime mover 8. This blower is adapted to take the products of combustion from a small furnace 9 and propel them through the duct 6 and thence into the ash-pits of the several fireplaces of the kiln. The blower is arranged also to discharge fresh air into the ash-pits when desired, after the manner of conventional forced-draft systems, or it can discharge a mixture of air and combustion products. A branch passage 10 leads also from the duct 6 to the ash-pit of the small furnace 9. Dampers or valves 11 and 12 are provided at suitable points to control the flow, all as will be plain from the drawings. The usual fuel feed openings 13 are provided for each grate in the kiln and are covered by the usual swinging feed doors 14, which will be

readily understood. The green bricks are stacked on the floor 2 in arched formation over the respective fire places and in individually spaced relation so as to permit the products of combustion to pass through the mass and escape at the top surface which is covered by a layer of platting bricks, as usual.

Heretofore it has been the practice to water-smoke the green bricks by building slow fires in each of the fireplaces, keeping the combustion down so as to provide heat only sufficient for the purpose of drying out the clay and without firing it. This step has ordinarily required some 48 to 72 hours, depending more or less upon the nature of the clay. Thereupon, water-smoking having been completed, the fires have been quickened to the temperature desired and maintained at such temperature until the burn has been finished, the last step taking some 72 to 96 hours, making a total of about 144 hours for the entire process. The bricks then taken from the kiln are of various qualities, as is very well known, depending upon the thoroughness and particularly the uniformity with which they have been previously water-smoked and the skill and thoroughness with which they have been fired. It is customary for a large proportion of the bricks to become lost or seriously impaired in value from imperfect water-smoking and particularly from the fact that the slow fires used for that purpose form so-called chimneys through the stack of green bricks which tends to localize the heat and flame of the fires when quickened for the step of firing. These chimneys are produced by the heating of the bricks immediately above the water-smoking fires; which by reason of their higher temperature create an upward draft at that point through the stack. The flame from the quickened fire naturally follows this up-draft course rather than seek the surrounding cooler bricks and is for this reason apt to over-burn the bricks where the chimneys are and generally near the heads of the kiln. I have been able to eliminate the difficulties from this cause by the method constituting the present invention and according to which I perform the step of water-smoking the green bricks by blowing either hot air or the products of combustion from the furnace 9 through them.

Most efficiently I use the products of combustion of the furnace 9 passing such products through the duct 6 and its several branches above described into the ash-pits 5 of the several fireplaces, from which it rises into and through the stack. The pressure of this hot air or gas and the velocity at which it moves from the blower insures that it permeates the entire stack of green 10 bricks in the kiln, without the formation of chimneys. I carry on this water-smoking step for a period of about thirty hours, although the step is not limited to this length of time and will of course vary with the 15 circumstances. I then build preliminary fires on the extreme inward ends of the grates 4, for instance, on the innermost grate section or the two innermost sections, placing a sheet metal plate such as shown in 20 position at 15 (Fig. 1 and left-hand side of Fig. 2), over the outermost sections so as to close up the grate openings thereof. These fires are purposely disposed in the position stated so as to be approximately under the 25 quarters of the stack and inwardly of the heads of the stack and preferably they are placed as nearly directly under the quarters as possible. I regulate the combustion of 30 these fires by partly opening the doors 14, and thereby I keep up a moderate rate of combustion, for a period of from eighteen to twenty hours, although this length of time is subject to variation and depends upon the refractoriness of the clay being 35 treated. These slow fires under the quarters, or inward of the heads will not produce chimneys in the kiln. I then remove the plates 15 and enlarge the fires, at the same time stimulating the combustion up to the 40 full or normal rate customary for firing bricks, and for this purpose I use a forced draft from the blower 7, and preferably such blower is connected with the furnace 9, so as to deliver the products of its combustion or partial combustion to the ash-pits 45 of the kiln fireplaces. By then utilizing the branch passage 10 which leads to the ash-pit of the furnace 9, I am able to produce an effluent in the latter consisting partially 50 of $C O_2$ which serves to produce lengthened flames from the kiln fires, that will extend well into and through the stack. I continue this last step for about thirty hours, more or less, until the bricks are burned. On 55 cooling, the bricks will be found to be more uniformly burned and to a more even quality than is possible with any of the present methods of firing, all of which, as will be observed, is accomplished in a shorter period of time.

The combustion taking place in each fire-

place in the kiln, both during the step of moderate heating which immediately follows the drying by hot gas and also during the high firing, is to be regulated at each 65 fireplace by the appropriate adjustment of the dampers 12 above referred to, it being desirable and important that the heating of the stack be as uniform as possible throughout its entire mass. 70

I claim:

1. In the manufacture of bricks the process which consists in building and maintaining restricted fires substantially under the quarters of a stack of bricks in a kiln, 75 utilizing for such purpose a portion only of the normal grate area of the kiln, and then enlarging such fires over the whole of the grate surface and quickening the same for normal firing. 80

2. In the manufacture of bricks, the process which consists in water-smoking a stack of green bricks in a kiln by passing heated gas therethrough, heating such stack by means of slow fires disposed inwardly of 85 the head ends of the stack and then heating the stack by larger and quicker fires to the point required for normal firing.

3. In the manufacture of bricks, the process which consists in water-smoking a stack 90 of green bricks in a kiln by passing a heated gas therethrough, heating such stack by means of restricted fires disposed substantially beneath the quarters of the stack and then enlarging and quickening such fires to 95 effect the burning of the clay.

4. In the manufacture of bricks, the process which consists, first, in water-smoking a stack of green bricks by means of heated gas under pressure above atmosphere, second, 100 by moderately heating such stack by means of one or more fires disposed inwardly of the head ends of the stack, and, third, by highly heating the stack to burn the clay. 105

5. In the manufacture of bricks, the process which consists, first, in water-smoking a stack of green bricks by means of heated gas under pressure above atmosphere, second, by moderately heating such stack by means of one or more fires disposed substantially 110 under the quarters thereof, and, third, by highly heating the stack by one or more fires which are operated with a forced-draft containing combustion gases.

In testimony whereof I have signed this 115 specification in the presence of two witnesses.

JOHN C. QUINN.
